UNITED STATES PATENT OFFICE.

ELLSWORTH TILDEN, OF DULUTH, MINNESOTA

SOUNDING SIGNAL DEVICE FOR AUTOMOBILES.

1,312,370.

Specification of Letters Patent.

Patented Aug. 5, 1919.

Application filed February 19, 1919. Serial No. 277,938.

To all whom it may concern:

Be it known that I, ELLSWORTH TILDEN, a citizen of the United States, residing at Duluth, in the county of St. Louis and State of Minnesota, have invented certain new and useful Improvements in Sounding Signal Devices for Automobiles; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in an alarm locking device for use upon automobiles, and consists of a simple device of this character, which will be given an alarm in the event of the automobile to which it is applied being used while the device is set.

The invention comprises a simple and efficient device of this character having various details of construction, combination and arrangement of parts which will be herein-after fully described, shown in the accompanying drawings and then specifically defined in the appended claims.

I illustrate my invention in the accompanying drawings which, with the letters of reference marked thereon, form a part of this application, and in which:

Figure 1 is a side elevation of the device.

Fig. 2 is a central sectional view, and

Fig. 3 is a transverse sectional view.

Reference now being had to the details of the drawings by letter:

A and B designate two sections of the casing, which are preferably of cylindrical outline, and are held spaced apart by means of the straps C. Mounted within the casing A is a cylindrical outlined block D with its upper surface E dished, and having a central opening F in the bottom thereof. H designates an alarm bell fastened within the section A immediately above and adjacent to the upper dished surface of the block D. Mounted upon the central axis between the

space intermediate the two sections are two disks I and K, having peripheral numbers L and perforations N, identified by each numeral and formed in the disks adjacent to the marginal edge thereof. When said disks are adjusted in place their outer peripheries

will be flush with the outer faces of the sections of the casing.

Mounted within the lower section A of the casing is a tube O which is slotted down from its upper end upon its inner portion, and Q designates a rod mounted to have a longitudinal movement within said tube, and is provided with a lateral extending handle P passing through a slot in the casing section A, and forming means whereby the rod Q may be raised and lowered. A second rod Q' is also mounted within the tube O and is given an upper longitudinal movement through the medium of the rod when the latter is raised. The rod Q' has a laterally extending L-shaped arm Q² extending through the slot in the tube O and having at its outer free upturned end a concaved recess Q³ adapted to receive a ball R. The under surface of the block D has a radial channel D' formed therein, in which said L-shaped arm is adapted to move the ball, being held at all times centrally in alinement with the hole F in the block D. A washer Q⁴ is mounted about the rod Q' and is adapted to bear with sufficient friction against the wall of the tube in which it is mounted to hold the same in different adjusted positions.

Mounted within the section B is a tubular casing T having a rod T' mounted therein, and S is a knob fastened to the rod and passed through a slot in the casing section B. Said rod T' has an integral lug T² adapted to conform to and pass through apertures N' and N² when the same come in registration with each other and underneath the pin T'. It will be noted that the rod T' and the perpendicularly disposed portion of the rod Q' are in alinement with each other, and when the perforations N and N² in the two disks, representing certain combinations, are brought into registration with each other, the rod T' may be pushed down through the registering apertures and against the top of the rod Q' for the purpose of returning the same to its lowest and normal position, the ball moving down also by gravity and resting in the recess in the end thereof.

In operation, the device is adapted to be attached to any suitable part of an automobile, such as the running-board and when the driver leaves the automobile in the street or other place, the signal device is set by raising the button P attached to the rod Q,

raising the rod and with it the tube within the L-shaped extension forcing the ball to the surface of the block D where it will roll back and forth against the bell and sound the alarm. The arm holding the ball in position to sound the alarm will be held in its raised position until returned by pushing down upon the rod T' having a handle or knob S projecting therefrom, but before it is possible to move the rod T so that it will push the rod Q to its normal position, it will be necessary to know the combination of disks, so that the disks may be rotated to bring certain numerals designating the apertures N' and N² together, one above the other, which will indicate that said apertures are in position to permit the lug T² to pass through the two disks. It will be noted that the lug T² is located a slight distance from the lower end of the pin T' and which will permit said lower end to always engage one or another of the several apertures in the upper disk, which will lock the same from rotating, the lower disk, however, being free to rotate until the two particular apertures N' and N² are brought into registration with each other and in alinement with the pin T'.

By the provision of a signal device embodying the features of my invention, it will be noted that means is provided whereby any tampering with an automobile will be readily detected by the signal which will be sounded by the ball rolling against the bell.

35 What I claim to be new is:

1. A sounding signal of the type described, comprising a casing made up of two sections spaced apart, rotatable disks with perforations therein mounted within the spaces between the disks and having peripheral numerals identifying the perforations in the disks, a block within the lower section having its upper surface dished and provided with a central aperture, a bell positioned over said dished portion of the block, a ball and support therefor, and means having a part extending outside the casing for raising said support and which will raise the ball through the aperture in the block and permit the ball to roll against the bell, and

means for returning the ball to its normal position.

2. A sounding signal of the type described, comprising a casing made up of two sections spaced apart, rotatable disks with perforations therein mounted within the spaces between the disks, and having peripheral numerals identifying the perforations in the disks, a block within the lower section having its upper surface dished and provided with a central aperture, a bell positioned over said dished portion of the block, a ball and support therefor, and means having a part extending outside the casing for raising said support and which will raise the ball through the aperture in the block and permit the ball to roll against the bell, a movable rod mounted in the upper section and having a knob extending outside the casing adapted, when certain apertures of the disks are in registration, to be permitted to pass through the same to return said support and ball carried thereby to their normal positions.

3. A sounding signal of the type described, comprising a casing made up of two sections spaced apart, rotatable disks with perforations therein mounted within the spaces between the disks, and having peripheral numerals identifying the perforations in the disks, a block with the lower section having its upper surface dished and provided with a central aperture, a bell positioned over said dished portion of the block, a vertically movable rod having a lateral extension, and ball carried thereby, means for raising said rod to permit the ball to enter the dished portion of the block, a rod in the upper portion of the casing in alinement with the rod in said lateral extension, and designed to be passed through said combination of apertures in the disks to return the rod carrying said ball to its normal position.

In testimony whereof I hereunto affix my signature in presence of two witnesses.

ELLSWORTH TILDEN.
